Inventor,

Frederick W. Drostend

UNITED STATES PATENT OFFICE.

FREDERICK W. DROSTEN, OF ST. LOUIS, MISSOURI.

GRATING-MACHINE.

SPECIFICATION forming part of Letters Patent No. 351,100, dated October 19, 1886.

Application filed February 8, 1886. Serial No. 191,232. (No model.)

To all whom it may concern:

Be it known that I, FREDERICK W. DROSTEN, a citizen of the United States, residing at the city of St. Louis, in the State of Missouri, have invented a new and useful Fruit, Vegetable, and Nut Grating Machine, of which the following is a specification.

My invention relates to improvements in fruit, vegetable, and nut graters or grating-machines which operate with a rotating metal disk or drum, having a raised or grater surface which cuts off small particles of the kernel or substance intended to be grated and allows it to pass through it into a vessel provided to receive it; and the object of my invention is to provide a continuous bearing of the matter to be reduced while in the hopper in course of being grated against the revolving grating disk or surface, and thus insuring its speedy and complete trituration and reduction to any desired consistency, which may be determined by the size and shape of the openings and raised cutting-surface of the revolving disk or surface. I attain these objects by the mechanism illustrated in the accompanying drawings, in which—

Figure 1 is an elevation of my machine, having a portion of the front broken off so as to show the interior parts in place. Fig. 2 is a vertical section through the center of the machine on line 2 of Fig. 1. Fig. 3 is a cross-section of the upper part of Fig. 1 on line 3 thereof, looking from below, and showing the position of the oblique bearing-flanges on the inner side of the hopper or receiver. Fig. 4 is a detail showing the annular grating-disk. Fig. 5 is a detail of the annular grating-disk, showing the raised cutting-edges. Fig. 6 is another detail view of the annular cutting or grating disk, showing the grating edges and orifices enlarged.

Similar letters refer to similar parts throughout the several views.

The body A of the grater is round, and made of tin, sheet-iron, brass, or other suitable material, having its middle cone-shaped or inclined inwardly and terminating in a neck and dish-shaped top or mouth, and is open at the bottom.

A metal bridge, A², Fig. 2, provided with a fixed hollow metal shank a in which the central

connecting vertical rod or shaft, B, is journaled, spans the top or upper part of the body.

The central shaft or rod, B, Fig. 2, is square at the top, or so as to engage the arm or crank D, by which the grater is operated, and is provided with a shoulder or rest, b, bearing on the hollow shank a, through which the rod passes and engages the annular grating-disk C in the middle at C², Fig. 2, where the rod is made 55 square, or so as to have a bearing for and engage and hold the disk firmly by the nut and washers C⁴ and C⁵ that work on the threaded lower end of the rod.

The grating-disk C, Figs. 4 and 6, is made 65 round and fits snug enough to move freely between the inside walls of the body of the grater A. The forms of the cuts and edges that do the grating may be round, oval, oblong, or square, or all of these, and similar forms may 70 be provided with each grater, and may be put in or taken out with little trouble at the will of the operator.

The flanges E, Fig. 3, are made of tin or other sheet metal cut into triangular shape and soldered or otherwise fastened at one side thereof to the sloping inner walls of the body of the grater, and projecting downwardly therefrom in an oblique direction toward the diameter of the body of the grater at an angle of about 80 forty-five degrees, where it rests and is fastened to one end of the braces or supports E'. The supports E' are also made of sheet metal, and are soldered to the inclined inside walls of the body of the grater at one end and to the 85 flanges E at the other, and thus support the said flanges at the angle of their slope from the body downward, the same being on a line with the motion of the disk C, as indicated by the dotted lines and arrows, Figs. 1, 2, 4, and 6. 90 The front surface of these flanges engages the material to be grated at an angle as soon as the disk C is set in motion, and prevents the same from escaping until the whole is brought in contact with the grating-surface of the disk and 95 reduced, the flanges passing directly over the grating-surface just enough to free the points on the disk.

It is obvious that the parts or whole of the foregoing machine may be made larger or 100 smaller as occasion may require, and may be operated by steam or hand power in any of the

well-known means of giving motion to a central shaft; but the chief object which I seek is to provide a utensil ready at hand for the house-keeper's use in grating any of the things required and adapted for being reduced in a family grater.

Among the advantages of my improved grater may be mentioned its simplicity of construction and operation and readiness of taking 10 apart for the purposes of cleaning or inserting different forms of grating-surface disks suited to the different kinds of work desired.

Having thus described my apparatus, what

I claim as my invention, and desire to secure by Letters Patent, is—

The combination, in a grater, of the body A, having downwardly-inclined prismoidal flanges E E', bridge A², shaft B, grater-disk C, and means for securing said disk to the shaft, substantially as described, and for the purposes 20 set forth.

FREDERICK W. DROSTEN.
